UNITED STATES PATENT OFFICE.

CLARENCE B. HAYNES, OF CAMDEN, NEW JERSEY, ASSIGNOR OF TWENTY-TWO AND ONE-HALF ONE-HUNDREDTHS TO CHARLES A. RICHARDSON AND TEN ONE-HUNDREDTHS TO WILLIAM K. B. RICHARDSON, BOTH OF HADDONFIELD, NEW JERSEY, AND TWENTY-TWO AND ONE-HALF ONE-HUNDREDTHS TO MAX LIVERIGHT, OF PHILADELPHIA, PENNSYLVANIA.

CARBURETER.

1,143,961.

Specification of Letters Patent. Patented June 22, 1915.

Application filed January 29, 1914. Serial No. 815,145.

To all whom it may concern:

Be it known that I, CLARENCE B. HAYNES, a citizen of the United States, residing at Camden, in the county of Camden, State of New Jersey, have invented a new and useful 5 Carbureter, of which the following is a specification.

My invention consists of a carbureter for internal combustion engines in which means 10 are provided for finely comminuting the liquid fuel and thoroughly mixing the same with moistened air.

It further consists of means for regulating the feed of the liquid fuel into the carbureter.

It further consists of means for adjusting the comminuting and mixing devices.

It further consists of other novel features of construction, all as will be hereinafter 20 fully set forth.

The annexed drawings and the following description set forth in detail one mechanical form embodying the invention, such detail construction being but one of various mechanical forms in which the principle of the 25 invention may be used.

In said annexed drawings—Figure 1 represents a vertical section of my improved carbureter, taken on the line $\alpha-\alpha$ in Fig. 3. 30 Fig. 2 represents a side view of said carbureter. Fig. 3 represents a top plan view of the carbureter.

Similar numerals of reference indicate corresponding parts in the figures.

35 Referring to the drawings, the reference numeral 1 indicates the carbureter casing which communicates with the intake of the engine by a laterally and upwardly extending duct, 2, in which a throttle-valve, 3, is 40 preferably located. A laterally extending and curved chamber, 4, is secured to the lower end of the carbureter chamber and has a bracket, 5, to which the lower head, 6, of a float-chamber, 7, is secured. Said chamber 45 has an upper head, 8, and gaskets, 9 and 10, are arranged in said heads and have the ends of a cylindrical wall, 11, preferably of glass, bearing against them, the heads being secured together and clamping such 50 wall and gaskets by means of an axial screw-bolt, 12, having a head, 13, bearing against a washer, 14, and passing through the center

of the upper head and the chamber, and screwing into the center of the lower head. A float, 15, is guided by an axial tube, 16, 55 upon the screw-bolt to rise and fall within the float-chamber with the level of the liquid fuel within the same. A passage, 17, extends laterally from the bottom of the float-chamber, and communicates with the lower end of a tube, 18, having its upper end closed by a screw cap, 19, and having a perforated guide nut, 20, screwed in its upper end, within which a stem, 21, of a needle-valve, 22, is guided. Said needle-valve is adapted to 60 fit on a seat, 24, in a nipple, 25, to which a fuel-supply pipe 26, is connected. A helical spring, 27, is wrapped around the valve-stem and bears against the guide-nut and a collar, 28, upon the stem, tending to force 65 the valve on to its seat. A lever, 29, is fulcrumed at about its middle upon a transverse pin, 30, in the passage, and has a forked end, 31, straddling the valve-stem and bearing from below against the collar 70 upon the valve-stem. The opposite end of said lever bears against the under side of the float 15, so that the weight of the latter will be counter-balanced by the spring on the valve-stem.

80 A bearing, 32, is formed within the chamber 4 and in axial alinement with the carbureter casing, and said chamber has an annular shoulder, 33, upon which the lower edge of said casing is seated, and an internal, 85 annular, beveled seat, 34. A stem, 35, of a needle-valve, 36 is located in said bearing and has a screw-thread, 37, at its lower portion, engaging an internally threaded portion, 38, of the bearing, and a cap, 39, is 90 screwed upon a nipple, 40, upon the outside of the chamber 4 to close the bearing, and the lower end of the valve-stem has a handle, 41, for turning it. A channel, 42, extends from the lower end of the float-chamber into the 95 bearing, and a screw-threaded portion, 43, of a tubular shank, 44, of a plug, 45, is secured in the upper end of the bearing and has a seat, 46, in its lower end for the needle-valve. An enlarged chamber, 47, is formed 100 in the extension of the needle-valve bearing, surrounding the shank of the plug and communicating with the tubular interior of the same through ports, 48. The plug is bev-

eled, and the upper end of the enlarged chamber has a bevel, so that an outwardly flaring annular slot, 49, is formed. A flaring hood, 50, surrounds the spray-nozzle formed by the extension and plug, and its lower edge is in adjustable proximity to the beveled seat in the carbureter chamber to form a narrow annular port. The upper portion of the hood has a number of openings, 51, communicating with the carbureter chamber. A stem, 52, is secured to the top of the hood and is slideable in a neck, 53, in the lower end of a cylinder, 54, extending through the top of the carbureter chamber, and has a piston, 55, at its upper end slideable in said cylinder and having a spring, 56, bearing against it and adjusted by means of a cap, 57, threaded upon the upper end of the cylinder and engaged by a lock, 58, which prevents it from turning after adjustment. A dome-shaped screen, 59, is secured in the carbureter chamber above the dome, and may be composed of a plurality of foraminated screens, 60.

25 The laterally extending, curved chamber 4 has its outer end turned upward to form an elbow, 61, into the upper internally screw-threaded end of which is screwed a cylinder, 62, having perforations, 63. A head, 64, is secured upon the upper end of said cylinder and has a reservoir, 65, secured upon it, having an opening, 66, to which a pipe or other connection to a liquid-supply may be connected. A helix, 67, of 30 felt or other absorbent material, is supported in the moistening chamber formed from the perforated cylinder and the elbow, and has a helical core, 68, of wire or similar material for supporting it and maintaining it in its 35 shape. The lower end of said core is secured by a nut, 69, in the bottom of the moistening chamber, and the upper end of the absorbent helix fits tightly in a hole in the head of the moistening chamber and 40 passes into the reservoir, where a nipple, 70, fits over such end and is held in position by a nut, 71, secured upon the upper screw-threaded end, 72, of the core. While a helix 45 is preferable on account of offering a large 50 evaporating surface in proportion to the space it occupies, it is evident that any other tortuous shape may be given to the evaporating body.

In practice, the fuel pipe is connected to 55 the float-chamber and the duct 2 is connected to the intake of the engine to which the device is applied, and suitable connection is made from the reservoir to a supply of water.

60 When the engine is started, suction will be created in the intake, and fuel will be drawn from the float-chamber and air will be drawn from the moistening chamber, passing up through the hood, where it will 65 mix with the vaporized spray of fuel issuing

through the outwardly flaring spraying slot 49 and pass through the perforations in the top of the hood. The mixed fuel and air passes upward through the domed screen and through the duct and throttle-valve to 70 the engine. Perfect mixture of fuel and air will take place by the thin annular and flaring spray of fuel striking the inner sides of the hood and mixing with the air ascending through the hood and then passing out 75 through the perforations in the same, whereupon such mixture is again mixed with air passing upward on the outside of the hood and fully comminuted and mixed in the domed screen. The air passing in through 80 the perforated walls of the moistening chamber will at all points within said chamber come in contact with the surface of the absorbent helix, which is saturated with water, so that the air will absorb a large proportion 85 of moisture and produce a highly explosive mixture.

The proportion of fuel can be accurately adjusted by the needle float-valve, the needle-valve 36 for the flaring spray-nozzle 90 and the tapering plug of said spray-nozzle.

The flaring hood will be raised against the pressure of the spring 56 by the suction from the engine, so that the air-supply is automatically gaged by the requirements of 95 the engine, and the tension of the spring is adjusted by its screw-cap.

The air-moistening device forms the subject-matter of a separate application, sworn to by me on the 17th day of January, 1914, 100 and forms no part of the present invention, as far as its particular construction is concerned.

The float-chamber performs the ordinary 105 functions of such a chamber, and does not materially differ in construction and operation from well-known float-chambers of that type.

The entire device is simple of construction 110 and all parts are easy of access for cleaning and repair. The float-cup and moistening chamber are supported at diametrically opposite sides of the carbureting chamber, so that said elements balance one another, and the fuel and air inlets will be direct into 115 and close to the carbureting chamber, so that there is slight liability of obstruction of passages and gumming from the fuel passing through long passages.

Other modes of applying the principle of 120 my invention may be employed for the mode herein explained. Change may therefore be made as regards the mechanism thus disclosed, provided the principles of construction set forth respectively, in the following 125 claim are employed.

Having thus described my invention, what I claim as new and desire to secure by Letters Patent, is:—

In a device of the character stated, a car- 130

bureter casing having a bottom opening and fuel-communizing means within it, a float-chamber supported at one side of the carbureter chamber and having a channel connected to said comminuting means, a curved duct having one upturned end connected to the bottom-opening of the carbureter chamber and extending laterally oppositely to

the float-chamber, and an air-moistening chamber secured in the outer upturned end 10 of said curved duct.

CLARENCE B. HAYNES.
